ERNEST H. SCHMIDT, OF CLEVELAND, OHIO, ASSIGNOR TO THE NATIONAL MALLEABLE CASTINGS COMPANY, OF CLEVELAND, OHIO, A CORPORATION OF OHIO.

SHOCK-ABSORBING MECHANISM.

1,228,831.

Specification of Letters Patent. Patented June 5, 1917.

Application filed November 30, 1915. Serial No. 64,203.

To all whom it may concern:

Be it known that I, ERNEST H. SCHMIDT, a citizen of the United States, and a resident of Cleveland, Cuyahoga county, Ohio, have invented new and useful Improvements in Shock-Absorbing Mechanisms, of which the following is a specification, reference being had to the accompanying drawings, in which—

10 Figure 1 is an elevation, partly in section, of my improved mechanism; Fig. 2 is a vertical section thereof; Fig. 3 is a plan, partly in section, thereof; Fig. 4 is a section on lines IV—IV of Fig. 2; Fig. 5 is a section on lines V—V of Fig. 1; Fig. 6 is an elevation partly in section showing a modification of my device, and Fig. 7 is a plan, partly in section, thereof.

15 My invention relates to shock absorbing mechanisms of the type in which the frictional elements are comprised of a plurality of friction shoes arranged about a central friction member, and consists in the elimination of the usual casing and in a novel arrangement of stops and releasing members. My invention also consists in the construction and coöperation of the parts which I shall hereinafter describe and claim.

20 Referring to the drawings, 2 indicates a central friction member preferably formed at its rear end into an enlarged plate or base 3 of rectangular shape, which is designed to abut against the usual draft sill stops (not shown) attached to the car structure. The central friction member has friction shoes 4 bearing in its reentrant angles, and the wedges 5 and 6 bear against the friction shoes, forcing them inwardly against the central friction member. The foremost wedge 5 preferably comprises the front follower, also intended to bear against draft sill stops.

25 To the rear of the rearmost set of shoes is an intermediate follower 7, which bears against the one end of the compression spring 8, which surrounds the central friction member 2, being held in position thereby, and bears at its opposite end against the forward face 9 of the base 3. Seated in apertures 10 in the base 3 and held loosely therein by pins 11^a are stop members 11, of which I have shown four, which move with the base 3 and slide in sockets 12^a in the front wedge or follower 5 and bear against

the face 13 of the front follower at the end of the buffing movement, so as to take up and transmit excessive buffing stresses and thereby prevent damage to the gear.

30 Mounted on the stop members are the release or restoring springs 14, which at one end bear against the forward face 9 of the base and at the other end against forward faces of the shoulders 15 on the collars 12 slidably mounted on the stops 11 and abutting 35 against the forward wedge 5. The parts are held in operative relation by the bolts 16 which at one end seat in apertures 17 in the base 3 and at the other end in apertures 18 in the front wedge 5. Castellated 40 nuts 19 are employed on the bolts 16, so that the parts may be held under slight initial compression. When the nuts 19 have been 45 adjusted to give the proper compression they are held in position by means of the 50 cotters 20.

55 The operation of my device is as follows: In buffing, the front follower 5 will transmit the buff through the friction shoes 4 and wedge 6 to the central friction member 2 and through the intermediate follower 7 to the compression spring 8, which bears 60 against the base 3 of the friction member. The face 13 of the front wedge or follower is so arranged that it will strike the forward ends of the stop members 11 at the end 65 of the travel of the device and just before the parts go solid, so as to permit the excessive buffing strains to be taken up by the base 3 direct from the front follower 5, and thereby relieve the frictional parts from 70 excessive stress.

75 In draft, the base 3 and the central friction member 2 will move forwardly, while the front follower or wedge 5 will be held 80 against movement, and the spring 8, with the intermediate follower 7 and wedges 5 and 6 will force the friction shoes 4 against the friction member 2. Just before the device goes solid the forward ends of the stop 85 members bear against the face 13 of the front follower or wedge 5, thus again acting to transmit excessive stresses of the draft to the front follower.

90 After the stresses of buffing or draft have 95 ceased, the release or restoring springs 14, reacting against shoulder 15 of the collar 12 at one end and the face 11 of the central friction member at the other end, will relieve 100 the wedging engagement between the fore- 105

110

most wedge and its set of shoes, and the forward faces of the shoulders 15 of the collar 12 will engage the projections 21 on the wedge 6 and drive it forwardly, thus releasing the second set of shoes and permitting the parts to assume their normal position in the device.

My device is of great advantage, since it provides a rigging of light weight and of 10 simple and strong construction. The central friction member supports the compression spring 8, the shoes 4, the wedges 5 and 6 and the follower 7, while the stop members 11 support the restoring springs 14 and are 15 in turn supported by the foremost wedge and base 3. As the frictional and spring parts of the device are thus self supporting, the usual casing is thus unnecessary.

In Figs. 6 and 7 I have illustrated a modified form of my invention, employing only 20 two releasing springs 14', which are supported on the securing bolts 16' instead of on the stop members 11'. I have also shown the inner faces of the outer portions of the 25 base 3' and follower 5' provided with raised compression pads 22, which take up the pressure from the stop members 11' as the gear goes solid.

The terms and expressions which I have 30 employed are used as terms of description and not of limitation, and I have no intention, in the use of such terms and expressions, of excluding any mechanical equivalents of the features shown and described, or 35 portions thereof, but recognize that various structural modifications are possible within the scope of the invention claimed.

What I claim is;

1. In frictional shock absorbing mechanism a cushioning element comprising friction members and a compression spring, a pair of followers, longitudinally extending stop members seated in sockets in said followers, said stop members being secured to and movable with one of said followers and 40 being capable upon movement of the device to slide in sockets in the other follower, said stop members comprising means for limiting the compression of the device.

2. A combined wedge follower for frictional shock absorbing mechanism, substantially rectangular in form, having parallel outer and inner plane faces, inclined faces intermediate said outer and inner faces, said inner face being apertured for the reception 50 of stop members, and said outer face having at its inner side a plurality of raised compression pads adapted to receive pressure from the stop members.

3. A combined friction member and follower for frictional shock absorbing mechanism, having a longitudinally extending frictional portion comprising a plurality of radiating arms, a rear base portion of substantially rectangular form, having parallel 60 outer and inner plane faces, said inner face forming a seating surface for springs and being apertured for the reception of stop members, said outer face having at its inner 65 side a plurality of raised compression pads 70 adapted to receive pressure from the stop members.

ERNEST H. SCHMIDT.
